UNITED STATES PATENT OFFICE.

EUGENE T. TURNER, OF HOLMES, NEW YORK, ASSIGNOR TO EUGENE T. TURNER
LABORATORIES, INC., OF NEWARK, NEW JERSEY, A CORPORATION OF NEW
JERSEY.

VARIABLE INDUCTANCE.

Application filed March 22, 1921. Serial No. 454,557.

To all whom it may concern:

Be it known that I, EUGENE T. TURNER, a citizen of the United States, and a resident of Holmes, Dutchess County, and State of New York, have invented certain new and useful Improvements in Variable Inductances, of which the following is a specification.

My present invention relates to radio communication and transmission of energy.

Special objects of the invention are to provide an inductance adaptable to the various requirements of radio work, which can be quickly and accurately adjusted and connected in various relations and which will be of particularly compact, simple and sturdy construction, with the coil elements protected against mechanical injury.

These and other objects are attained in the structure illustrated in the accompanying drawing forming a part of this specification and which typifies one of the practical forms the invention may take.

Figure 1 is a plan view of the device with the top of the box shown broken away to disclose the intermediate primary coil and with the movable doors and coil supports indicated both in fully open and partly closed positions.

Figure 2 is a front view of the device with the coil-carrying doors shown in fully open position, the front wall of the box in this case being broken away to disclose the intermediate or relatively fixed coil.

Figure 3 is a broken detail and partly sectional view of the intermediate coil construction.

As shown in these views, the invention comprises a box or casing for housing the coils, which is open at opposite sides and there provided with doors or closures which serve also as adjustable carriers or supports for the inductively related coils.

As illustrated, this box comprises fixed top and bottom walls 5 and 6 rigidly connected by front and back walls 7 and 8. The open frame thus provided is closed at the opposite sides thereof by movable doors 9 and 10.

These doors or closures are shown as hingedly supported at the rear between the top and bottom 5 and 6 and means are provided for releasably securing the same in the various angular relations to which they may be adjusted. These boxes are usually con-

structed of wood or similar material and when this is the case, the means for thus securing the doors may consist, as shown, of wood screws 11, 12 passed through the top and bottom into the edge portions of the doors, there being sufficient friction in this type of joint to yieldingly hold the doors at the points where they are set.

The apparatus of the present disclosure is provided with three coils, the intermediate relatively fixed primary coil 13, the secondary coil 14 and the so-called "tickler" coil 15, the latter two being supported on the inner faces of the doors and being therefore shiftable as the doors are opened and closed, to vary the relative inductance.

All three coils are shown as of the flat spiral type covered by my Patent #1,372,850, and consisting each of a wire wound spirally in the slots between the radiating arms of a flat insulating disc. These flat cores support the convolutions of the wire and serve in the present disclosure also as a means for mounting the coils, the cores 16 of the door-carried coils having screws 17 passed therethrough into the doors and the core 18 of the intermediate coil being engaged in a circular seat 19 provided in the supporting partition 20 which is held in grooves 21 formed in the top and bottom of the box. This last-mentioned core is shown as held in its seat by clips 22 which may be of the ordinary paper-fastener variety.

The coils are supported on the doors so that when the doors are fully closed, as shown in dotted lines in Figure 1, the three coils will stand in closely juxtaposed relation. To bring about this relation, spacers 23 may be interposed at the back of the coils on the doors, these spacers being of sufficient extent to hold the coils at the proper distance from the face of the doors so that when the doors are closed, the coils will be brought close together. This spacing of the coils from the doors also provides room for the leading-out wires 24.

The back wall 8 at the hinge edge of the box is also utilized as a support for the terminals. In the illustration this wall, which is made of wood or other insulating material, carries a pair of binding posts or terminals 25 for the coil 15, a pair of terminals 26 for the intermediate coil 13 and a pair of terminal posts 27 for the other door coil 14. These binding posts are all freely acces-

sible at the back of the box so that connections with external circuits may be readily made.

With this invention, it will be seen that when the device is not in use and the doors are closed, all three coils will be fully protected and that even when adjustments are being made, the coils will be, to a large extent, protected by the doors which carry them. These doors serve as convenient hand-holds for shifting the coils and both outstanding coils may be separately adjusted with respect to the center coil and each will remain in the position at which it has been set.

What I claim is:

1. In a variable inductance, a box provided with oppositely disposed hinged doors, coils supported in opposed relation on said doors and a cooperating coil supported within the box between the independently adjustable door-supported coils.
2. In a variable inductance, a box provided with opposed hinged doors, a coil fixedly supported in the box in the space between the hinged doors and cooperating coils mounted on the inner faces of the doors and adjustable in the movement of said doors toward and away from said fixed coil.
3. In a variable inductance, a box provided with a hinged door at one side thereof, a coil supported within said box and mechanically protected thereby, a coil mounted on the hinged door and positioned to be brought into opposed relation to the first coil as the cover is closed and whereby relative adjustment of the two coils is provided for and both coils are protected from mechanical injury when the cover of the box is closed, a hinged door at the opposite side of the box and a third coil, carried by said door and adapted to be positioned thereby in inductive relation to the coil within the box.
4. In a variable inductance, a relatively narrow box whose opposite sides are formed by hinged doors, inductively related flat coils mounted on and carried by said doors toward and away from each other as the doors are closed and opened and a flat coil supported within the box in inductive relation

to and between the door-carried coils, said flat door supported coils being offset inwardly from the inner faces of the doors so as to be thereby carried into close inductive relation to the box coil as the doors are closed.

5. In a variable inductance, a box open at opposite sides and having fixed front and back, top and bottom walls, doors closing the open sides of the box and hinged between the top and bottom walls and cooperating inductance coils carried by said hinged doors and adjustable relative to each other in the opening and closing movements of the doors, and a stationary coil supported in the box between the fixed top and bottom walls.

6. In a variable inductance, a coil box open at opposite sides and having fixed front and back, top and bottom walls, hinged doors closing the open sides of the box and cooperating inductance coils carried by said doors at the inner faces thereof and relatively adjustable in the opening and closing movements of the doors, and a stationary coil supported in the box between the fixed top and bottom walls.

7. In a variable inductance, a coil box open at opposite sides and having a fixed back wall, hinged doors for closing the open sides of the box, coils mounted on and carried by said hinged doors and exposed terminals for said coils mounted on the fixed back wall of the box.

8. In a variable inductance, a coil box open at opposite sides and having relatively fixed top and bottom and rear walls, terminals carried by said rear wall, a coil supported between the top and bottom walls, movable doors closing the open sides of the box and inductance coils mounted on and carried by said hinged doors.

9. In a variable inductance, a coil box having slots in opposite walls thereof, a coil support engaged in said slots, a coil carried by said support, a movable door for the box and a coil carried by said door and inductively related to the first-mentioned coil.

In witness whereof, I have hereunto set my hand this 9th day of March, 1921.

EUGENE T. TURNER
